Atty.

UNITED STATES PATENT OFFICE.

WILLIAM J. MORGAN, OF ST. LOUIS, MISSOURI, ASSIGNOR, BY DIRECT AND MESNE ASSIGNMENTS, TO ALFRED L. EUSTICE, OF CHICAGO, ILLINOIS.

INCLOSED ELECTRIC FUSE.

1,074,806.

Specification of Letters Patent.

Patented Oct. 7, 1913.

Application filed August 5, 1912, Serial No. 713,332. Renewed August 20, 1913. Serial No. 785,819.

To all whom it may concern:

Be it known that I, WILLIAM J. MORGAN, a citizen of the United States, residing at the city of St. Louis, State of Missouri, have 5 invented a certain new and useful Improvement in Inclosed Electric Fuses, of which the following is a specification, reference being had to the accompanying drawings, forming a part hereof, in which—

10 Figure 1 is a perspective view of an inclosed electric fuse embodying my invention; Fig. 2 is a longitudinal sectional view therethrough; and Fig. 3 is a sectional view of the line 3—3, Fig. 2.

15 This invention relates to a certain new and useful improvement in inclosed electric fuses.

Inclosed electric fuses of the class to which my invention is particularly applicable are 20 usually made up of or comprise an open ended tubular casing preferably of suitable fibrous material closed at its ends by metallic caps, through which caps, in the form of fuse shown in the accompanying drawings, 25 pass into the interior of the casing contact blades or terminals which are bridged across within the casing by means of a fusible element having a current carrying capacity less than the current carrying capacity of said 30 blade terminals and adapted to carry the current up to a certain rated amperage and to blow or fuse on an overload or increased current and thereby protect the electric circuit in which the fuse may be arranged, as 35 will be well understood. In other forms of fuses, and particularly of fuses adapted for use with currents of comparatively small voltage, the fusible element may be directly attached at its ends to the caps which close

40 the ends of the tubular casing. Within the casing and surrounding the fusible element is a filling of suitable material, preferably in a finely-divided state, such as slaked lime, the function of which is to dissipate the heat 45 and provide minute paths or interstices for the escape of the vapor or gas arising or evolved upon the fusing or blowing of the fusible element.

On the blowing of the fusible element, 50 usually only the fusible element and the surrounding filling are affected, the remaining parts of the fuse remaining intact and uninjured, and generally heretofore, on the blowing of the fusible element, the entire fuse 55 either had to be discarded and thrown away

or disrupted and taken apart to supply or furnish the same with a new filling and with a new fusible element. The object of my invention is to so construct a fuse of the kind stated, whereby, on the blowing or fusing of 60 the fusible element, the melted or fused particles thereof and the affected filling there-around may be readily and quickly removed from the casing and a new fusible element and a new filling readily placed within the 65 casing without requiring or necessitating the dismantling and consequent re-assembling of the main elements of the fuse, resulting in a saving in labor and material and reducing the cost of replacing burnt-out or disrupted 70 fuses.

With this object in view, my invention resides in the provision of a fuse of the class stated having a closable opening and means for normally closing the same, whereby, on 75 the disrupting of the fusible element, the affected filling and melted or fused particles of the fusible element may be easily and readily removed and replaced by a new element and filling, the closure for said opening 80 forming, when in closed or normal position, a part of the casing of the fuse, and in certain novel features of construction, arrangement, and combination of parts, all as will hereinafter be described and afterward 85 pointed out in the claims.

Referring by numerals to the accompanying drawings, the fuse there shown comprises an open ended tubular casing 1, preferably of suitable fibrous material, and 90 which casing may be of any suitable length and diameter as desired according to the size or required carrying or rated capacity of the fuse.

2—2' indicate metallic cup-shaped caps 95 which are suitably fixedly secured, as by means of screws or the like 3, on, and which are adapted to close, the ends of casing 1.

4—4 indicate blade terminals which project through caps 2—2' a suitable distance 100 into the interior of casing 1 at its opposite ends, as shown particularly in Fig. 2, and bridging the space between the inner ends of terminals 4 within casing 1 and suitably electrically connected thereto, as by metallic 105 screws or the like 5, is a fusible element 6 having a current carrying capacity less than the current carrying capacity of blade arms 4—4 and adapted to fuse or blow on an overload or on an increase in current over 110

its rated capacity. Surrounding this fusible element 6 and filling the interior of casing 1 is a filling 7 of any suitable material, preferably in a finely divided state, such as slaked lime, adapted to dissipate the heat and provide minute paths or interstices for the escape of the vapor or gas arising or evolved upon the fusing or blowing of the fusible element.

- 10 Casing 1 is longitudinally cut away to provide a circumferential preferably rectangular opening, as at 1^a, through which access may be had from the exterior into the interior thereof and to said filling 7 and fusible element 6, one end of said opening being preferably flush with the edge of cap 2 and said opening extending at its other end somewhat under and beyond the edge of cap 2', as shown particularly in Fig. 2.
- 15 20 Adapted to neatly and tightly fit in said opening 1^a, so that, when in normal position closing said opening, its outer face will be flush with the outer face or periphery of casing 1, as shown in Fig. 1, is a closure 25 8 substantially arc-shaped in cross-section and of material preferably similar to or like the material of casing 1. As shown particularly in Fig. 2, this closure 8 is adapted, when in normal position, to project at one end beneath the edge of cap 2' and be thereby at that end secured in position. To firmly secure closure 8 in normal position at its other end, I have provided a short 30 35 preferably metallic section or plate 9, which is fixed within casing 1 by means of a pin or stud 10 passing through said plate, casing 1, and cap 2, this plate 9 extending at one end beneath one end of opening 1^a, and to which plate 9 said end of closure 8, when closure 8 is in normal position, is removably firmly secured by means of a short screw or the like 11, as shown particularly in Fig. 2. As will be seen, this closure 8, when in normal position, practically forms part of casing 1, the edges of closure 8 and of opening 1^a of casing 1 being preferably oppositely beveled, so that, when closure 8 is in normal position, said edges neatly match and a substantially airtight joint is formed therebetween.

On the blowing of fusible element 6, it will be apparent that, by unscrewing screw 11, closure 8 may be readily removed from its seat, when old or used filling 7 and the melted or fused particles of blown fuse 6 may be readily removed without requiring or necessitating a dismantling, and consequent reassembling, of the remaining parts of the fuse, and a new filling and element placed in position within casing 1, when cover or closure 8 may be again secured in closed or normal position.

I may here state that I have found that a fuse constructed in accordance with, and embodying, my invention will safely meet

and withstand the most severe service tests and, in every way, fully perform and accomplish the object hereinbefore stated; and while I have herein shown and described my invention as applied to, or in connection with, an inclosed fuse of a particular construction, it is to be understood that my invention may be equally well applied to inclosed fuses varying in construction therefrom.

I am aware that minor changes in the construction, arrangement, and combination of the several parts of my invention may be made and substituted for those herein shown and described without departing from the nature and principle of my invention.

Having thus described my invention, what I claim and desire to secure by Letters Patent is:

1. In a fuse, an open ended tubular casing, cup-shaped caps arranged on, and closing, the ends of said casing, said casing being longitudinally provided with an elongated circumferential opening through which access may be had from the exterior into the interior thereof, an elongated closure substantially arc-shaped in cross-section for removably closing said opening, a short metallic section fixed within said casing and projecting below said opening, and a screw adapted to pass through said closure and seat in said metallic section to removably secure said closure to said casing; substantially as described.

2. In a fuse, an open-ended tubular casing, cup-shaped caps arranged on, and closing, the ends of said casing, said casing being longitudinally provided with an elongated circumferential opening through which access may be had from the exterior into the interior thereof, an elongated closure substantially arc-shaped in cross section for removably closing said opening, one end of said closure lying under the projecting edge of one of said caps when said closure is in normal closing position, and means adapted to removably secure the other end of said closure to said casing; substantially as described.

3. In a fuse, an open ended tubular casing, cup-shaped caps arranged on, and closing, the ends of said casing, said casing being longitudinally provided with an elongated circumferential opening through which access may be had from the exterior into the interior thereof, an elongated closure substantially arc-shaped in cross-section for removably closing said opening, one end of said closure lying under the projecting edge of one of said caps when said closure is in normal closing position, a short metallic section fixed within said casing and projecting at one end below said opening, and a screw adapted to pass through said closure and seat in said metallic section to

removably secure the other end of said closure to said casing; substantially as described.

4. In a fuse, an open ended tubular casing, 5 cup-shaped caps arranged on, and closing, the ends of said casing, said casing being longitudinally provided with an elongated circumferential opening through which access may be had from the exterior into the 10 interior thereof, an elongated closure substantially arc-shaped in cross-section for removably closing said opening, one end of said closure lying under the projecting edge of one of said caps when said closure is in 15 normal closing position, a short metallic section fixed within said casing and projecting

at one end below said opening, and a screw adapted to pass through said closure and seat in said metallic section to removably secure the other end of said closure to said casing, the outer faces of said casing and said closure being substantially flush when said closure is in normal closing position; substantially as described. 20

In testimony whereof, I have signed my 25 name to this specification in the presence of two subscribing witnesses.

WILLIAM J. MORGAN.
